UNITED STATES PATENT OFFICE.

FREDERICK THOMAS, OF PHILADELPHIA, PENNSYLVANIA.

ARM FOR CREEASING AND LIKE MACHINES.

Application filed October 26, 1922. Serial No. 596,943.

To all whom it may concern:

Be it known that I, FREDERICK THOMAS, a citizen of the United States, residing at Philadelphia, in the county of Philadelphia and State of Pennsylvania, have invented a new and useful Improvement in Arms for Creasing and like Machines, of which the following is a specification.

Objects of the present invention are to apply steam to the edge of the cloth or part of the cloth that is to be turned in creasing; to avoid staining any part of the material that would show even if water were accidentally applied to it along with the steam; to diminish the pressure required for creasing a fabric; and to provide convenience in changing the dies. Other objects of the invention will appear from the following description at the end of which the invention will be claimed after having been first described in connection with the embodiment of it chosen from other embodiments for the sake of illustration in the accompanying drawings forming part hereof and in which—

Figure 1 is a top or plan view of an arm for creasing and like machines embodying or containing features of the invention.

Fig. 2 is a side view of the same, partly in section, and illustrating diagrammatically features of the invention.

Fig. 3 is an end view, partly in section, looking toward the right in Fig. 2.

Fig. 4 is an end view or inverted plan of the head of the arm.

Fig. 5 is a top or plan view with parts broken away of the die.

Fig. 6 is a sectional view drawn to an enlarged scale and taken on the line 6—6 of Fig. 5, and

Fig. 7 is a sectional view drawn to an enlarged scale and taken on the line 7—7 of Fig. 4.

In the drawings 1 is a head arranged at the end of the arm 2, and it is provided with a gasket receiving recess 3 and with a projecting steam nozzle 4 communicating with the steam channel 5 provided in the arm. 6, generally, is a hollow die detachably connected with the head 1 as by means of screws 7 and wing nuts 8. The die is provided with an opening 9 to its hollow interior 10, and this opening 9 is adapted for the reception of the steam nozzle 4. The gasket 11 arranged in the recess 3 around the nozzle 4 provides with the die a steam tight joint

the parts of which are detachable. The die is provided with lateral steam discharge orifices 12 arranged to discharge in the plane of the die and onto the edges *a*, Figs. 2 and 3, of the fabric which the die is adapted to turn up. As shown the die consists of upper and lower plates 13 and 14 spaced apart by spacers 15 and riveted together. The spacers 15 are washers strung on the rivets and disposed between plates 13 and 14, and so the plates while secured together are spaced apart, and this is one way of providing the orifices 12, and in this case the orifices are bounded by the plates 13 and 14 and by the spacers 15. The lower plate 14 extends beyond the edge of the upper plate 13. Where creasing is to be accomplished, for example, in Fig. 5, at the bottom and sides of the die, the spacers 15 assume the form of rings and at the other edge they assume the form of a strip. Steam is supplied to the channel 5, and this may be done by pipe connections 16 which include a valve 17.

To change the die it is released from the head by the simple operation of taking off the wing nuts 8, and another die can be applied and secured by means of the wing nuts. The steam joint between the head and die requires no attention when the dies are changed. When the die is applied to the fabric *a*, the plate 14, in co-operation with the table *b* and elements *c* of a creasing machine, operates to turn up the fabric as shown at *a*, and the valve 17 being opened, steam is discharged in the plane of the die and onto the edges of the fabric. If the steam carries water, the water will reach only the turned parts of the fabric and even if water stains the fabric, no harm will be done because the edges of the fabric do not show in the finished garment. Steam applied to the edges greatly facilitates their being creased, consequently comparatively little pressure is sufficient for properly operating the die.

It will be obvious to those skilled in the art to which the invention relates that modifications may be made in details of construction and arrangement without departing from the spirit of the invention which is not limited in respect to such matters or otherwise than as the prior art and the appended claims may require.

I claim:

1. An arm for creasing and like machines

comprising in combination a head arranged at the end of the arm and having a gasket recess and a projecting steam nozzle communicating with a steam channel provided in the head, a hollow die detachably connected with the head and having an opening to its interior adapted for the reception of the nozzle and having lateral steam discharge orifices arranged to discharge in the plane of the die and onto the edges of the fabric which the die is adapted to turn up, and a gasket in said recess around said nozzle.

2. An arm for creasing and like machines comprising in combination a head having a steam channel through it, and a hollow die detachably attached to the head with its interior in communication with the steam channel and provided with an imperforate face for contact with the fabric and with lateral discharge openings arranged to discharge in the plane of the die and onto fabric turned up by it.

3. An arm for creasing and like machines

provided with a die having an imperforate face for contact with the fabric and having lateral steam discharge openings arranged to discharge in the plane of the die, substantially as described.

4. An arm for creasing and like machines having a steam channel through it and having a hollow die internally in communication with the channel and provided with edgewise discharging steam outlets and with an imperforate face.

5. A machine of the type described having a die provided with steam outlets arranged to discharge in the plane of the die and with an imperforate face.

6. A machine of the type described having a die consisting of plates spaced apart with steam discharge openings at their edges and connected together and of which one is of larger area than the other and is imperforate in combination with means for supplying steam to the space between said plates.

FREDERICK THOMAS.
